UNITED STATES PATENT OFFICE.

JOHN H. HANLON, OF SOMERVILLE, MASSACHUSETTS, ASSIGNOR TO HANLON LOCOMOTIVE SANDER COMPANY, OF WINCHESTER, MASSACHUSETTS, A CORPORATION OF MASSACHUSETTS.

TRACK-SANDER.

1,265,711.

Specification of Letters Patent.

Patented May 7, 1918.

Application filed September 13, 1917. Serial No. 191,097.

To all whom it may concern:

Be it known that I, JOHN H. HANLON, a citizen of the United States, residing at Somerville, county of Middlesex, State of Massachusetts, have invented a certain new and useful Improvement in Track-Sanders, of which the following is a specification, reference being had therein to the accompanying drawings.

10 My invention has for its object an improvement in track sanders for use on locomotives and relates particularly to a so called outside sander which is applied to the outside of a sand box. It has been found 15 in the past that outside sanders are advantageous because they are accessible in case repair work is necessary. For this and other reasons a large demand has arisen for them, and consequently, many locomotive sand 20 boxes are cast with a base to which the outside sander may be attached. Outside sanders as heretofore constructed wear out rapidly and frequently do not deliver sand enough to the rails; furthermore, their construction is such that they cannot be properly 25 regulated and the amount of sand delivered to the wheels is often not under proper control.

The object of my present invention is to 30 overcome these difficulties and to provide a sander which will feed an increased amount of sand to the wheels of the locomotive and which may be controlled by the engineer so that any given quantity of sand may be applied to the rails. The sander embodying 35 my invention is a combination gravity feed and air blast sander. It is so constructed that a direct flow of sand is provided and the force of the air blast is not cut down, so 40 that the sand may be driven through the sand pipe a sufficient distance to deliver sand to any of the drivers with enough force to insure its being delivered to the rails. Owing to the flow of the sand directly into the 45 sand pipe, the metal casting is worn away by the action of the sand much less rapidly than has heretofore been the case, and will last for a great length of time without needing to be renewed. No lead bushings or 50 caps which must be replaced at frequent intervals are required, thus greatly increasing the economy of operation. Furthermore, the sander is particularly adapted to be

readily attached to the usual base with which the sand box is provided, and may be 55 equipped with any desired number of sand nozzles, so that as many nozzles as needed may be used on any type of locomotive with the use of a single sand box.

The invention will be fully understood 60 from the following description when taken in connection with the accompanying drawings, and the novel features thereof will be pointed out and clearly defined in the claims at the close of this specification. 65

In the drawings, Figure 1 is an elevation of a sand box located on a locomotive boiler and provided with a device embodying my invention, a portion only of the boiler shell being shown. 70

Fig. 2 is an enlarged view partly in section of a track sander embodying my invention which is provided with four sand blast nozzles. 75

Fig. 3 is a view similar to Fig. 2, showing a sander provided with two sand blast nozzles.

Fig. 4 is a section on line 4-4 of Fig. 3.

Having reference to Fig. 1 of the drawings, at A is shown a portion of the upper 80 surface of a locomotive boiler upon which is mounted a sand box B of any usual construction. The sand box B has the usual base and is provided at two opposite sides with bosses C of any usual form, to which 85 the sanders D, embodying my invention, are secured in the customary manner. The sanders D are particularly intended for use on locomotives having sand boxes of the present well known construction and are 90 applicable to them without any change whatsoever.

The sander D is a combination gravity and air blast sander, as is the case with the usual outside sander, and for this purpose is 95 provided with a pair of gravity feed openings 11 and 12 and a pair of sand inlet passages 13, only one of which is shown as seen in Fig. 2, through which the sand ejected by the air jets is supplied. The sander casting 100 D consists of a face plate 15 having bolt holes 16 by which it may be secured to the sand box boss C in the usual manner, the gravity feed openings 11 and 12 and the sand inlet passages 13 being arranged to coincide with corresponding passages through 105

the boss C. These passages are not shown but are of the usual construction, and communicate with the interior of the box.

The face plate 15 has downwardly projecting arms 17 and 18 at its ends through which the passages 13 extend, the arms being cast integral with the face plate. The gravity passages 11 and 12 are threaded for attachment with pipes 19 and 20 which may be secured to the outside of the locomotive boiler and arranged to direct the sand on the wheels in the usual manner, the flow of sand being controlled by gates or sand valves of any well known form, located within the sand box and not shown in the drawings.

The sander D is also provided with air blast nozzles, one of which is contained in each of the arms 17 and 18. These arms are similar in their construction and therefore the arm 17 will be referred to only. The arm 17 inclines downwardly as shown in Fig. 1. The sand inlet passage 13 therein receives sand from the sand box by gravity. The passage 13 extends through the arm 17, and may be closed by a plug 21, as shown in Fig. 3, or connected with another sand blast nozzle as shown in Fig. 2, as will be herein-after described. At one side of the arm is a horizontal passage 22 which is threaded to receive a pipe 23. Directly opposite the passage 22 is an air blast nozzle 24 having a longitudinal passage 25 extending through it, and forming an air discharge orifice. There is preferably also a transverse passage 26 which intersects the passage 25 and is located near the inner end of the nozzle. An air chamber 27 is formed in the wall of the arm 17 and is closed at one side by a threaded plug 28 having a recess 29 in its inner face. The nozzle 24 extends through the wall between the sand inlet passage 13 and the air chamber 27 and its inner end is located in the recess in the plug 28.

At the upper end of the chamber 27 is a port 30 to which is secured a pipe 31 (see Fig. 1) adapted to supply compressed air and controlled by an engineer's cab valve, not shown, in the usual manner. The air from the port 30 is directed down through the chamber 27 toward a well 32 extending through the lower end of the arm 17 and closed by a screw plug 33. The well 32 is thus arranged so that it will catch all the sediment, scale and like dirt brought in with the air. It may be readily cleaned out by removing the plug 33.

The nozzle 24 is horizontally disposed and is so arranged that the passages at its inner end are within the recess in the plug 28 and are protected by it. In the past, great difficulty has been experienced owing to the tendency of air nozzles to become completely plugged with air sediment and the like so that no sand will be discharged through the sand discharge pipe without

taking the sander apart and cleaning the air nozzle. Although attempts have been made to prevent this, the difficulty has not been entirely overcome. The construction herein disclosed is especially designed to 70 remedy this trouble. The inner ends of the air passages 25, 26 in the nozzles are located completely within the recess in the plug 28 so that the air which is directed downwardly from the port 30 toward the 75 well 32 passes by the inner end of the air passages and deposits the sediment and the like in the well 32 before it enters the passages. If the passage 25 in the air nozzle becomes plugged, it may be readily cleaned 80 out by removing the plug 28 and passing a wire directly through the nozzle. This can be done quickly and without loss of sand; neither is any special tool necessary.

The arrangement of the nozzle 24 in the 85 sand chamber 13 is also an important feature of my invention. As is well known to those skilled in the art, there is a tendency for the end of the air passage in the nozzle to wear so that the passage becomes larger 90 than desired and more air than required passes through it. In outside combination sanders as heretofore constructed, so far as known to me, the air nozzle has of necessity been inclined upwardly and the sand particles striking against the end of the air passage have a tendency to wear it away at the sides. In the device embodying my invention the horizontal arrangement of the nozzle prevents the end from being hit by the 100 sand particles which in the old construction are blown up by the air blast and dropped down on the nozzle end. In this way the air passage does not become enlarged. This is important for I have found that the varying 105 sizes of air passages in sanders arranged at each side of the sand box so varies the amount of sand fed, that in many cases practically all the traction is obtained by the drivers on one side of the locomotive, with 110 the result that one set of drivers has a tendency to slip and to rack the locomotive parts.

In order that the sand chamber 13 may be cleaned out if it becomes plugged with 115 pebbles or stones contained in the sand, an opening is provided on the upper inclined surface of the arms 17 and 18 which is closed by a threaded plug 10 as shown in Fig. 4. This renders it possible to get at the chamber and remove any obstacle that 120 may be interfering with the operation of the device, and without loss of sand through the clean out opening.

By the arrangement and construction 125 shown herein, I am enabled to provide combination gravity and force feed sanders which do not receive any wear from the sand blast and therefore will last indefinitely. The air nozzle 24 propels the sand directly into the sand pipe 23 through 130

which it is conveyed to the wheels without any resistance save that which is occasioned by the walls of the pipe. The necessity of replacing sander castings or of providing lead bushings is thus done away with.

A further important feature of this construction is that the amount of sand supplied by the blast nozzle is greatly increased for the full force of the air is obtained and the maximum amount of sand is conveyed by it. In the construction heretofore employed, the resistance occasioned by the arrangement of the sander passage is very great so that the force of the air blast is materially diminished and accordingly the amount of sand conveyed is decreased to a marked degree. Furthermore, the resistance prevents the flow of sand from being properly regulated, whereas in the construction herein described, the flow of sand may be regulated so that the desired quantity of sand may be supplied to the wheels. This is important, for without proper regulation the engineer cannot control the traction of the drivers on each side of the locomotive, which should be substantially the same for otherwise great stress and strain is placed upon the locomotive parts.

The sander embodying my invention is arranged to supply sand from a single sand box to as many drivers of the locomotive as is desired. The construction of the sander nozzles by which a direct flow to the sand pipes is provided, affords sufficient force to propel the sand to any point on the engine without danger of clogging the sand pipes. Furthermore, each sander may be equipped with as many sander nozzles as are required, so that all the drivers of any type of locomotive may be supplied. In Fig. 2 of the drawings, my improved sander is shown as provided with four sand blast nozzles. More may be added if desired. The sand inlet passage 13 extends through the arm 17 and is directly connected with a passage 52 in a sander member 51 by means of a nipple 50. In the device shown in Fig. 2, the passage 52 is closed by a plug 53 but if more sander members should be desired, an additional sander member could be attached by replacing the plug 53 by another nipple 50.

The sander members 51, only one of which is shown in section in Fig. 2, are provided with an air blast nozzle 56 which is similar to the air blast nozzle 24 in the members 17 and 18, and is arranged to propel the sand directly into a pipe 55. The sand pipes are entirely separate from the gravity feed pipes and may be projected along the boiler of the locomotive as desired, in order to deliver sand to the drivers. This construction is an important improvement over sanders as heretofore constructed so far as known to me, for I am enabled to pro-

vide as many nozzles as I desire and to propel the sand the required distance so that all the drivers on both sides of the locomotive may be supplied by the use of one pair of sanders and a single sand box.

70

What I claim is:

1. The outside sander for locomotives provided with a sand box having a boss through which are separate passages for connection with a plurality of sand discharge passages, 75 said sander comprising a body for attachment to said boss and having independent sand passages therethrough registering with the passages in said boss, one of said passages constituting a gravity sander and the 80 other of said passages being intercepted at substantially right angles by a straight passage, there being an air nozzle opposite said discharge passage.

2. The outside sander for locomotives provided with a sand box having a boss through which are separate passages for connection with a plurality of sand discharge passages, 85 said sander comprising a body for attachment to said boss and having independent 90 sand passages therethrough registering with the passages in said boss, one of said passages constituting a gravity sander and the other of said passages being intercepted at substantially right angles by a straight 95 passage, there being an air nozzle opposite said discharge passage, and a plug closing an opening into said passage laterally opposite said air nozzle.

3. In a device of the character described, 100 a downwardly projecting member having a sand inlet passage therein, with an outlet passage at one side thereof, an air nozzle at the opposite side of said inlet passage, said member having an air chamber into 105 which said nozzle extends, at one side of which is a pocket in which the inner end of the nozzle is located, there being an inlet opening in said air chamber which is located at one side of said pocket. 110

4. In a device of the character described, 115 a downwardly projecting member having a sand inlet passage therein and an outlet passage at one side of the inlet passage, an air nozzle at the opposite side of said inlet 120 passage, said member having an air chamber into which said nozzle extends, and having an inlet opening and a plug detachably secured to said member at one side of said air chamber, having a recess therein forming a pocket in which the inner end of said nozzle is located, said pocket being located at one side of said inlet opening.

5. In a device of the character described, 125 a downwardly projecting member having a sand inlet passage therein, with a discharge passage at one side thereof, the axis of which is horizontal, a nozzle at the opposite side of said inlet passage and arranged to direct a blast of air straight through 130

said discharge passage, the axis of which is horizontal, said member having an air chamber with an inlet passage therein and a pocket at one side thereof, into which the inner end of said nozzle projects.

6. In a track sander, a body having a sand receiving chamber therein, and inlet and discharge passages connected therewith, there being an air chamber adjacent the sand receiving chamber and separated therefrom by a wall, an air nozzle projecting through said wall, a removable plug in the outside wall of said air chamber in line with said air nozzle, there being an air inlet opening into said air chamber.

7. In a track sander, a body, a sand receiving chamber therein, and inlet and discharge passages connected therewith, there being an air chamber adjacent the said receiving chamber and separated therefrom by a wall, an air nozzle affording an air passage through said wall and projecting both into the sand chamber and into said air chamber, a removable plug in the outside wall of said air chamber in line with said air nozzle, there being an air inlet opening into said air chamber.

In testimony whereof I affix my signature.

JOHN H. HANLON.
